UNITED STATES PATENT OFFICE

2,516,364

TRUCK ATTACHMENT

James Herbert Caddell, Richmond, Va.

Application February 13, 1947; Serial No. 728,285

3 Claims. (Cl. 212—65)

1 This invention relates to devices which are attached to trucks or other cargo-carrying vehicles for the purpose of providing means for loading or unloading articles carried thereby.

An important object of the invention is to provide a device of this character which can be attached to the vehicle itself, can be dismantled and carried within a comparatively small space during operation of the vehicle, and which can be assembled for loading or unloading operations in a short period of time.

Another important object of the invention is to provide a device of this character which can be mounted in various positions of adjustment and which embodies means for extension of various of its component parts, so as to provide for greatly increased versatility in cargo-loading or unloading.

It is a further object of the invention to provide a device of the character described which will fulfill all purposes for which it is intended and will yet be capable of being constructed comparatively inexpensively, of handling heavy loads, and of possessing unusual qualities of durability.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawing

Figure 1 is a side elevational view of the truck attachment constructed in accordance with the invention, with parts broken away.

Figure 2 is a top plan view.

Figure 3 is a fragmental transverse sectional view, showing a track and wheel attachment embodied in the invention, from which cargo-lifting means can be suspended.

Figure 4 is a fragmental sectional view showing a sleeve attachment embodied in the invention.

Figure 5 is a fragmental longitudinal sectional view showing adjustable means contained in a movable leg member embodied in the invention.

Figure 6 is a fragmental end elevational view, showing pivotal means for mounting the member mentioned in Figure 5.

2 Referring to the drawing in detail, the vehicle to which the invention is attached is indicated by the character reference 5. In the drawing and in this description, this vehicle is shown as a truck, but it is understood that the invention will have application as well to other cargo-carrying vehicles.

There is fixedly mounted on the truck, by suitable means, a cylindrical hollow base 6 which is preferably formed of a length of pipe material, within which there is vertically and removably mounted, for revolvable movement in the base 6, a cylindrical supporting member 7, which is also preferably formed of pipe material.

15 The upper end of the supporting member 7 is exteriorly threaded, and there is detachably mounted on the upper end a supporting member 8, which is approximately in the shape of a Y, having transversely aligned openings or bearings 20 in its ends of its arms and a cylindrical hollow base which has interior threads cooperating with the threads on the supporting member 7.

25 Mounted between the arms of the supporting member 8 is a cylindrical sleeve 9 having threaded trunnions 10 which are positioned in the bearings in the arms of the supporting member 8 for pivotal movement in said bearings, and which are secured therein by means of nuts.

The supporting member 8 is adapted to support within its sleeve 9, the front end of an extension arm 11 which will be described herein-after in detail, the rear end of the extension arm 11 being supported by a cylindrical vertical leg member 12, which is a composite member 30 preferably formed of lengths of pipe material.

Said leg member 12 is vertically and pivotally mounted on a dolly 13 which has a U-shaped bracket 14 mounted on its platform carrying transversely aligned bearing openings in its arms.

40 The lower end of the leg member 12 is tapered and also has a bearing opening, and is adapted to be positioned between the arms of the bracket 14 where it is pivotally mounted by means of a bolt extending through the bracket openings and the leg member opening. In addition, washers 15 are positioned between the leg member 12 and the arms of the brackets 14.

The leg member 12 is compositely formed in telescoping portions, the lower portion having 50 spaced vertically aligned openings 16 in its side for receiving the ends of an adjusting pin 17

which is positioned through a registering opening in the upper portion, thereby permitting the leg member to be fixed in various positions of longitudinal adjustment. The adjusting pin 17 is horizontally positioned through an opening in the end of a housing 18 attached to the sides of the upper portion of the leg member 12, the pin having a handle disposed exteriorly of the housing to facilitate manual operation, and being connected interiorly to the housing by a coil spring 19 having one end secured to the end of the housing and having its other end secured to the pin.

There is detachably mounted on the upper ends of the leg member 12 an elbow fitting 20, there being cooperating threads on the leg member and within the arm of the fitting for this purpose.

There is also an extension arm 11, as hereinbefore mentioned, which is of cylindrical form and is preferably formed of a length of pipe material, said arm having one end detachably mounted within the other arm of the elbow fitting 20.

The extension arm 11 is horizontally extended from the elbow fitting 20 and has its other end horizontally and slidably mounted in the sleeve 9. Said extension arm 11 is adapted to serve as a track for a rollable grooved wheel 21. There is also provided a U-shaped suspending member 22 which has transversely aligned bearing openings disposed in the ends of its arms, and said suspending member 22 is pivotally suspended from the wheel 21 by means of a bolt 23 which extends through the openings in the arms of the suspending member 22 and through the wheel 21 and is secured by means of nuts.

Pulley means 24 depend from the suspending member 22, providing means for lifting articles into or out of the truck 5, it being understood that other lifting means, rather than a pulley attachment, can also be used if desired.

In operating the truck attachment herein described, it will be seen that it is capable of being almost completely dismantled in order to be transported on the truck 5 to the point at which it is to be used. If desired, the supporting member 1 may be removed from the base 6, the sleeve supporting member 8 may be detached from the supporting member 7, the extension arm 11 removed from the sleeve, the elbow member 20 detached from the arm 11 and leg member 12, the leg member 12 telescoped to reduce its length to a minimum and the dolly 13 detached from the leg member 12.

In use, the attachment can be placed in a large number of positions of adjustment, as necessary to accomplish the particular loading or unloading tasks involved. The extension arm 11 can be positioned at any angle to a line drawn longitudinally through the truck 5, permitting loading or unloading from the side of the truck or the rear as necessary.

Further, the dolly 13 can be positioned on a level higher or lower than that on which the truck 5 rests, by reason of the telescoping arrangement embodied in the leg member 12. If necessary, the extension arm 11 may be inclined rather than horizontally positioned, by reason of the pivotal means embodied in the mounting of the sleeve 9 and in the mounting of the leg member 12. Thus, the dolly 13 may be positioned within a structure, such as a house, and the extension arm 11 extended through a door or other opening permitting direct movement of an article to or from its position within the structure or truck.

Further, it is possible to extend the length of the extension arm 11, not only by reason of its slidable mounting in the sleeve 9 but also by detaching it from the elbow fitting 20 and threading an extra length of pipe material onto its length, and into the elbow fitting. Similar means can be employed to extend the length of the supporting members 7 and 12 if desired.

What is claimed is:

1. In combination with a cargo-carrying vehicle, an attachment for loading or unloading articles transported within the vehicle, comprising a hollow cylindrical base fixedly and vertically mounted on the vehicle, a longitudinally extendable cylindrical supporting member formed of pipe material revolvably and removably mounted in said fixed base, a cylindrical sleeve pivotally and removably mounted on said supporting member, a longitudinally extendable leg member formed of pipe material removably and pivotally mounted on a movable base, an elbow fitting removably mounted on said leg member, an extendable arm formed of pipe material having one end removably mounted within the elbow fitting and having its other end slidably positioned within the aforesaid sleeve, a lifting means suspendably mounted on the arm, and wheel means rollably mounted on the extension arm for carrying the said lifting means.
2. In combination with a cargo-carrying vehicle, an attachment for loading or unloading articles transported within the vehicle, comprising a hollow cylindrical base fixedly and vertically mounted on the vehicle, a longitudinally extendable cylindrical supporting member formed of pipe material revolvably and removably mounted in said fixed base, a cylindrical sleeve pivotally and removably mounted on said supporting member, a longitudinally extendable leg member formed of pipe material removably and pivotally mounted on a movable base, said leg member having telescoping portions, there being vertically aligned openings disposed in one of said portions, a registering opening in the other portion, a housing communicating with the registering openings, an adjusting pin positioned within the housing and projecting exteriorly from the housing, a coil spring connected to the pin and being connected to the housing, an elbow fitting removably mounted on said leg member, an extendable arm formed of pipe material having one end removably mounted within the elbow fitting and having its other end slidably positioned within the aforesaid sleeve, a lifting means suspendably mounted on the arm, and wheel means rollably mounted on the extension arm for carrying the said lifting means.
3. In combination with a cargo-carrying vehicle, an attachment for loading or unloading articles transported within the vehicle, comprising a hollow cylindrical base fixedly and vertically mounted on the vehicle, a vertically extendable cylindrical supporting member revolvably and removably mounted in said fixed base, a cylindrical sleeve pivotally and removably mounted on said supporting member, a vertically extendable leg member removably and pivotally mounted on a movable base, said leg member having telescoping portions, there being vertically aligned openings disposed in one of said portions, a registering opening in the other portion, a housing communicating with the registering opening, an adjusting pin positioned within the housing and projecting exteriorly from the housing, a coil spring connected to the pin and to the housing,

an elbow fitting removably mounted on said leg member, an extendable arm having one end removably mounted within the elbow fitting and having its other end slidably positioned within the aforesaid sleeve, a lifting means suspendably mounted on the arm, and wheel means rollably mounted on the extension arm for carrying the said lifting means.
